LINING AND BEVELING MACHINE

Vernon Royle, Paterson, N. J.

Application May 29, 1929, Serial No. 367,008

8 Claims. (Cl. 90—58)

This invention relates to a lining and beveling machine, primarily designed for the use of engravers, and has for an object to provide such a machine in which the means for feeding the table which carries the work may be temporarily disconnected so as to permit quick and unhampered movement of the table during an inoperative stroke.

Another object consists in providing such a machine in which the work clamp is arranged to be bodily adjusted across the table.

Another object consists in providing such a machine in which the support for the table in its traveling movement includes anti-friction means.

Another object consists in providing such a machine in which the aligning gauge may be extended and adjusted across the table.

Another object consists in providing such a machine in which both the lining cut and beveling cut may be made on the same stroke of the table.

Another object consists in providing such a machine that includes improved means for feeding the table.

Another object consists in providing such a machine which includes improved means for adjusting the table laterally with respect to the work clamp.

A further object consists in providing certain improvements in the form, construction and arrangement of the several parts, whereby the above named and other objects may effectively be attained.

A practical embodiment of the invention is represented in the accompanying drawings, in which

Fig. 1 represents a side elevation of the machine;

Fig. 2 represents an elevation, partly in section, taken at right angles to Fig. 1;

Fig. 3 represents a plan view, partly broken away;

Fig. 4 represents a detail section taken in the plane of the line IV—IV of Fig. 3, looking in the direction of the arrows;

Fig. 5 represents a detail section taken in the plane of the line V—V of Fig. 3, looking in the direction of the arrows;

Fig. 6 represents a detail section taken substantially in the plane of the line VI—VI of Fig. 3, looking in the direction of the arrows;

Fig. 7 represents a detail elevation of the aligning gauge and adjacent parts;

Fig. 8 represents a detail plan view of the same;

Fig. 9 represents a detail plan view, showing a

different form of lining tool holder from that shown in Fig. 3;

Fig. 10 represents an elevation, partly in section, of the parts shown in Fig. 9.

The machine includes a base 1 arranged to be held in position by suitable lag screws, or the like, 2. From the base uprises a pedestal 3 to which is pivotally secured, as at 4, a motor support 5, on which is mounted a motor 6, by means of bolts 7. This motor receives a belt 8, which is designed to actuate parts hereinafter described. An adjusting screw 9 intervenes between the base 1 and motor support 5, by the use of which tension on the belt 8 may be adjusted through permitting the support 5 to swing downwardly under the influence of gravity or the reverse.

The part 10 represents a door swung on the pedestal 3 which permits access to the interior thereof for the storage of tools or other desired purpose.

A bracket arm 11 is fixed to the side of the pedestal 3 by cap screws 12 and projects upwardly therefrom in two angular directions, as clearly shown in Figs. 1 and 2. The upper end of the arm 11 carries a crosshead 13, which is secured thereto by bolts 13*; and at each extremity of this crosshead there is mounted a spindle 14 which is provided with anti-friction bearings for journaling the hub 15 of a wheel 16. A cap 17 serves to cover the end of the hub 15 and protect the spindle and bearings. The detail structure of only one of these wheels and its support is shown, but it will be understood that both wheels are identical and mounted in the same way. The same reference numerals are applied to each.

These two wheels 16 serve as an anti-friction support for one side of a carriage 18 which is reciprocated during the operation of the machine. The other side of the carriage is supported by a V-shaped rail 19 that is secured to the pedestal by bolts 20.

As a result of the construction just described, it will be seen that the carriage 18 is held in position and accurately guided by the rail 19, while the pair of wheels 16 adequately support the other side of the carriage and permit its reciprocating movement with a minimum of resistance. By projecting the arm 11 in two angular directions, the adjacent side of the carriage is properly supported throughout its travel.

The means for reciprocating the carriage 18 is well shown in Fig. 3, and includes a hand wheel 21 which is fixed to a rod 22 that is journaled in a swinging bearing 23 which is carried by a bracket

5

55

24 that is fixed to the side of the carriage. A screw bolt 25 serves as a pivot to permit the bearing 23 to swing in a vertical plane on bracket 24. The rod 22 pierces the adjacent side of the carriage 18, as indicated at 26, and its intermediate portion is provided with an enlargement 27 that is traversed by the enlarged part of an eccentric 28. One end of the eccentric is carried in a depending flange 29 formed on a plate 30, which is fixed on the carriage 18 by cap screws 31; and the other end of the eccentric is mounted in a cheek-piece 32 which is supported from flange 29 by through-bolts 33, that have their intermediate portions enlarged so as accurately to space cheek-piece 32 from flange 29.

10 The inner end of rod 22 is furnished with a helical gear 34 that normally meshes with a rack 35 that is clamped by the bolts 20 to track 19 and hence is fixedly secured to the pedestal 3.

20 From the preceding description it will be seen that turning the hand wheel 21 will slide carriage 18 on its track 19 and wheels 16 by virtue of the engagement of helical gear 34 with rack 35 and that the hand wheel 21 and connected parts 25 will travel with the carriage 18 in its movement. This provides a very smooth and positive action because of the character of the intermeshing parts and the traveling movement with the table of the actuating gear 34 and connected elements. A 30 helical gear, or the like, will always have at least two teeth in mesh with the rack because of the angularity of the teeth, which effects an even and precise movement; and such an arrangement also allows the shaft which operates the helical gear 35 to be placed at an acute angle to the rack, whereby its operating hand wheel may be convenient to the operator of the machine without being in his way. Furthermore, a gear of the helical type tends to prevent chips from clogging the rack, 40 because the engaging movement of the parts is such as to urge the chips out of the rack instead of to hold them therein and crush them.

45 While the table is intended to be reciprocated in the operation of the machine, it frequently happens that its movement in only one direction is an operative movement, and I have provided means for enabling the reverse or inoperative movement to be accomplished quickly and with small effort. This means contemplates a mechanism for temporarily disengaging the helical gear 34 from rack 35, which mechanism will now be described.

50 The bracket 36 is firmly clamped to cheek-piece 32 by the bolts 33, and its extremity is fashioned 55 to constitute a bearing 37 which carries a shaft 38, to the protruding end of which is fixed a rock arm 39 (see Fig. 4) and a segment gear 40. The gear 40 meshes with a pinion 41 that is fast on the end of eccentric 28. A link 42 connects one 60 end of rock arm 39 with an end of bell crank 43 that is pivoted at 44 in a bracket 45 fixed to a side of carriage 18. The other arm of the bell crank constitutes a hand grip 46 that cooperates with a fixed hand grip 47 which projects from bracket 65 45. A retractile spring 48 has one end fast to the extremity of rock arm 39 opposite to that where the link 42 is secured, and the other end fixed to carriage 18, thus normally holding the parts in such position that the grips 46 and 47 are separated. It will be seen that manual closing of the 70 said grips will rock the arm 39 and thereby move gear 40 so as to turn pinion 41 with which it meshes. This turning of the pinion will correspondingly turn eccentric 28 and thereby elevate 75 the adjacent portion of rod 22 so as to lift heli-

cal gear 34 out of engagement with rack 35. This elevation of the parts is permitted by turning movement of bearing 23 on pivot 25, as hereinabove indicated. This construction of the eccentric 28 is such that, when it is turned to the one position or the other, the parts will be locked against accidental return movement, so that there is no danger of the gear and rack accidentally becoming disengaged during the feed of the carriage or falling into engagement during the quick return movement thereof.

5 The construction of the parts thus set forth enables a workman to feed the carriage 18 on its working stroke with a comparatively slow and even motion by turning hand wheel 21, and, when 15 the operative stroke has been completed, to disengage the gear 34 and rack 35, whereupon the carriage may be returned to its original position quickly and easily by a direct pull thereupon without any rotation of hand wheel 21.

20 The table which directly carries the work is denoted by 49, and it is secured to the carriage 18 by screws 50 (see Fig. 3). These screws traverse slots 51 formed in flanges 52 on the carriage 18, and their ends are threaded into the under side of 25 table 49. Expansion springs 53 are interposed between the heads of screws 50 and flanges 52 so as yieldingly to hold the table clamped to the carriage.

30 The slots 51 and yielding springs 53 allow a small amount of lateral adjustment of table 49 on carriage 18, and this adjustment is accomplished by a screw 54 (see Fig. 3) the shank of which pierces a lug 55 that is bolted to the under side of table 49. The said shank is threaded into 35 a nut 56 which is fixed by a pin 57 in a yoke 58 that is fastened to and projects upwardly from the side of carriage 18. Turning the screw 54 will thus move the table 49 laterally across the top of carriage 18, because of the threaded engagement of the shank of the screw with nut 56. 40 A micrometer 59 is carried on the screw shank exterior to the edge of the table in order to facilitate exact adjustment of the parts.

45 The clamp 60 for securing the work to the table is herein briefly stated as being capable of moving vertically toward and away from the work and laterally across the table so as to facilitate the use of the machine on various occasions, particularly where a single plate containing a group 50 of pictures is being worked upon and it is, for instance, desired to line the boundaries of the individual pictures. The construction and operation of the clamp 60 and its actuating mechanism is, in part, the subject matter of my co-pending application, Serial No. 728,295.

55 The cutter head for the beveling and, if desired, channeling tool is of a well known and approved form. It is denoted by 86 (see Figs. 2 and 3) and is mounted on a spindle 87 which is journaled in 60 a bifurcated standard 88 that is carried on the upper part of pedestal 3. A pulley 89 is fixed to spindle 87, intermediate the arms of the bifurcated standard, and is intended to be embraced by belt 8 which leads from the motor, as hereinabove 65 described. The tools in the said cutter head 86 are indicated by 90, 91, and may be of any well known or approved form for the purpose in hand. A combined guard for the cutter head and chute for the chips is marked 92, and it is arranged so 70 as to lead the flying chips into receptacle 93 (see Fig. 1) which may be removed and emptied as desired, in accordance with a well known practice.

75 The machine also includes a head for a variety of lining tools, or the like, which is indicated gen-

erally by 94 (see Figs. 2 and 3). The detailed construction and operation of this head for the lining tools appears in United States patent granted to me jointly with Vernon E. Royle, under date of May 22, 1917 and No. 1,226,912, so that the same will not be shown or described herein. The said head is fixed on a slide 95 which has its side edges beveled and is mounted in an undercut track 96 that is carried on a support 97, which is 5 rotatably mounted on stud 98 that projects laterally from the side of standard 88. This rotatable mounting enables the tool head 94 to be swung into the operative position shown in Figs. 2 and 3 or to be swung upwardly and rearwardly to 10 inoperative position. The top of one side of track 96 is formed by a separate piece marked 99 that is traversed by a screw 100 which is threaded into the body of the track. Thus the part 99 serves, under the influence of the screw, as a clamp to 15 grip the edge of slide 95 and hold tool head 94 in its desired adjusted position. In order to provide for very accurate adjustment of this part, a sleeve 101 is adjustably fixed to slide 95 by a screw 102 which is yieldingly held in any desired 20 position by spring 103. The said sleeve 101 carries an adjusting screw 104 which is threaded therein and fitted to abut track 96. A micrometer gauge, 25 105 is provided on screw 104 for precise work.

It will be seen that, when it is desired to 30 adjust the head 94, screw 102 may be loosened and the slide 95 moved to approximately the desired position, at which point screw 104 will be then set, and the precise adjustment of head 94 accomplished by turning screw 104 that is provided 35 with the micrometer gauge. When the exact adjustment is obtained, clamp screw 100 may be tightened to hold the parts firmly in position.

The lining tool, or the like, carried by head 40 94 when in operation, is preferably mounted as indicated at 106 in Fig. 6, and it will be seen that this angular mounting of the tool is such that the line cutting can be done on the forward stroke of the table at the same time that the beveling is accomplished. This is a departure from 45 previous practice, in which the lining has been performed on the return stroke of the table, following the beveling operation.

The machine is further equipped with an aligning gauge that is well shown in Figs. 2, 3, 7 and 50 8. The said gauge includes a slide 107 that has beveled side edges which are mounted in an undercut track 108 rotatably mounted on a boss 109 that projects laterally from an arm 110 which is cast integral with a support 111 which is bolted 55 to and projects from the side of pedestal 3. Said rotatable mounting of track 108 enables the gauge to be swung into the operative position shown in Figs. 7 and 8 and into the inoperative 60 position shown in Figs. 2 and 3.

The forward end of slide 107 has a T-head 112 in the ends of which are fitted trunnions 113 that carry a frame 114 which supports the gauge proper 115. The latter is provided with the usual serrated edge to facilitate its use in exactly 65 predetermining the line to be cut on the work. A guard 116 is carried on the slide 107 and fitted to receive and cover the serrated edge of the gauge proper when the latter is not in use. This 70 protection is obtained by swinging the frame 114 on the trunnions 113 until the gauge proper 115 rests in the guard 116.

The construction of the parts for permitting 75 adjustment of the gauge is the same as that just described in connection with cutter head 94 so

that it will be sufficient merely to indicate the parts by number. The separate clamping member of the track is marked 117 and its screw 118. The sleeve on slide 117 is denoted by 119, its clamping screw by 120, the spring for the latter by 121, the micrometer adjusting screw by 122 and the micrometer by 123. It will be understood that these parts are arranged and operated in the same way as the corresponding parts associated with cutter head 94 and its slide 95. 10 This provision for extensive as well as for precise adjustment of the gauge across the top of the table, cooperates with the adjustability of the work clamp 60, to facilitate operation upon plates where it is desired to cut lines at a distance from the edges of the plates as, for instance, when a plate including a group of pictures is being operated upon. In order to prevent the gauge from striking a blow upon the table when it is swung into operative position, 15 I provide a stop 124 which is carried by the track 108 arranged to engage an abutment 125 on the arm 110 when the gauge has reached its operative position immediately above the table.

The lining cutter head 94 and its associated 20 parts and support may be bodily removed from the machine and substituted by the form of lining cutter head shown in Figs. 9 and 10, which latter is supported by a bracket 126 that is bolted to the side of standard 88. This form of 25 lining cutter head is denoted generally by 127 and, as its detailed construction and operation is set forth in my United States Patent No. 641,470, dated January 16, 1900, same will neither be shown nor described herein other than as generally indicated in Figs. 9 and 10 and already described. It may be observed that the cutting tool, which is marked 128 in Fig. 10 is set at the same angle as tool 106 in Fig. 6 for the purpose 30 hereinabove described in connection with the latter tool. The handle 129 is intended to be employed for holding the tool to the work in a well understood manner.

The part 130 (see Figs. 2 and 3) is merely a 35 tool tray that is conveniently supported from the back of rail 19; and it may here be mentioned that the other side of the said rail is grooved to receive the usual gib 131 that is fixed to the carriage 18 to prevent it from lifting on the rail.

The operation of the various parts of the 40 machine has been described in connection with setting forth their construction, so that it is not regarded as necessary here to restate the operation of the machine as a whole. It may, however, be noted that the construction and arrangement well adapts the machine for attaining the 45 objects hereinabove outlined and others inherent in its construction, and that its design contemplates efficiency, accuracy and speed in operation, together with general adaptability for 50 meeting the varying needs of this particular class of work.

It will be understood that various changes 55 may be resorted to in the form, construction and arrangement of the several parts without departing from the spirit and scope of my invention; and hence I do not intend to be limited to the details herein shown and described, except as they may be included in the claims.

What I claim is:

1. A machine of the character described comprising, a horizontally movable table and means for actuating the same, said means including a rack fixed on the machine below the inner edge of the table, a swinging bearing carried by the 75

outer edge of the table, a rod having its outer end journaled in said bearing and swingable therewith, an enlargement forming a bearing for the inner end of the rod, a gear on the inner end 5 of the rod normally engaging said rack, flanges depending from the bottom of the table, an eccentric journaled in the flanges in position to traverse and support said enlargement, and mechanism for rotating said eccentric in the 10 enlargement to actuate the rod and disengage the gear from the rack so that the table may be freely moved without operating the rod and gear.

2. A machine of the character described comprising, a horizontally movable table and means 15 for actuating the same, said means including a rack fixed on the machine, a swinging bearing carried by the table, a rod having its outer end journaled in said bearing and swingable therewith, an enlargement forming a bearing for the inner end of the rod, a gear on the rod normally 20 engaging said rack, an eccentric journaled in the table in position to traverse and support said enlargement, mechanism for rotating said eccentric in the enlargement in one direction to actuate the rod and disengage the gear from the 25 rack so that the table may be freely moved without operating the rod and gear, and a spring operated means for actuating said mechanism to rotate the eccentric in the enlargement in the other direction to move the rod and allow the 30 gear to engage the rack.

3. A machine of the character described comprising, a horizontally movable table and means 35 for actuating the same, said means including a rack fixed on the machine below the inner edge of the table, a swinging bearing carried by the outer edge of the table, a rod having its outer end journaled in said bearing and swingable therewith, said rod being mounted at an acute 40 angle to the line of movement of the table, an enlargement forming a bearing for the inner end of the rod, a helical gear on the rod normally engaging said rack, flanges depending from the bottom of the table, an eccentric journaled in the flanges in position to traverse and support 45 said enlargement, and mechanism for rotating said eccentric in the enlargement to actuate the rod and disengage the gear from the rack so that the table may be freely moved without operating the rod and gear.

50 4. A machine of the character described comprising, a horizontally movable table and means for actuating the same, said means including a rack fixed on the machine, a swinging bearing carried by the table, a rod having its outer end 55 journaled in said bearing and swingable therewith, said rod being mounted at an acute angle to the line of movement of the table, an enlargement forming a bearing for the inner end of the rod, a helical gear on the rod normally engaging 60 said rack, an eccentric journaled in the table in position to traverse and support said enlargement, mechanism for rotating said eccentric in the enlargement in one direction to actuate the rod and disengage the gear from the rack so 65 that the table may be freely moved without operating the rod and gear, and a spring operated means for actuating said mechanism to rotate the eccentric in the enlargement in the other direction to move the rod and allow the gear to 70 engage the rack.

5. A machine of the character described comprising, a pedestal, a movable table carried thereby and offset laterally from the pedestal, frictional

and anti-frictional supports disposed to engage the bottom of the table adjacent the longitudinal edges thereof, said frictional support comprising a rail and groove arranged adjacent the pedestal to guide the table longitudinally and prevent lateral displacement, and a straight rearwardly inclined arm having its lower end fixed to one side of the pedestal below the inner longitudinal edge of the table and arranged to project laterally and upwardly therefrom for carrying the anti-frictional support in position to engage the bottom near the outer longitudinal edge of the table, whereby greater accessibility of the work on the table is obtained.

6. A machine of the character described comprising, a pedestal, a movable table carried thereby and offset laterally from the pedestal, frictional and anti-frictional supports disposed to engage the bottom of the table adjacent the longitudinal edges thereof, said frictional support comprising a rail and groove arranged adjacent the pedestal to guide the table longitudinally and prevent lateral displacement, a straight rearwardly inclined arm having its lower end fixed to one side of the pedestal below the inner longitudinal edge of the table and arranged to project laterally and upwardly therefrom, and rotatable members spaced apart and carried by the upper end of said arm in position to engage the bottom near the outer longitudinal edge of the table, whereby greater accessibility of the work on the table is obtained.

7. A machine of the character described comprising, a pedestal, a movable table carried thereby and offset laterally from the pedestal, frictional and anti-frictional supports disposed to engage the bottom of the table adjacent the longitudinal edges thereof, said frictional support comprising a rail and groove arranged adjacent the pedestal to guide the table longitudinally and prevent lateral displacement, a straight rearwardly inclined arm having its lower end fixed to one side of the pedestal below the inner longitudinal edge of the table and arranged to project laterally and upwardly therefrom, a cross head secured to the upper end of said arm and disposed in parallelism with the rail and groove, and rotatable members spaced apart and journaled in said cross head in position to engage the bottom near the outer longitudinal edge of the table, whereby greater accessibility of the work on the table is obtained.

8. A machine of the character described comprising, a pedestal, a movable table carried thereby and offset laterally from the pedestal, frictional and anti-frictional supports disposed to engage the bottom of the table adjacent the longitudinal edges thereof, said frictional support comprising a rail and groove arranged adjacent the pedestal to guide the table longitudinally and prevent lateral displacement, a straight rearwardly inclined arm having its lower end fixed to one side of the pedestal below the inner longitudinal edge of the table and arranged to project laterally and upwardly therefrom, a cross head secured to the upper end of said arm and disposed in parallelism with the rail and groove, and rotatable members journaled in the opposite ends of said cross head in position to engage the bottom near the outer longitudinal edge of the table, whereby greater accessibility of the work on the table is obtained.

VERNON ROYLE.
